UNITED STATES PATENT OFFICE.

CHARLES WM. SQUIRES, OF BEVERLY, MASSACHUSETTS.

SWITCH-OPERATING MECHANISM.

1,199,831.

Specification of Letters Patent.

Patented Oct. 3, 1916.

Application filed February 4, 1914. Serial No. 816,498.

To all whom it may concern:

Be it known that I, CHARLES W. SQUIRES, of Beverly, in the county of Essex and State of Massachusetts, a citizen of the 5 United States, have invented a new and useful Improvement in Switch-Operating Mechanism, of which the following is a specification.

My invention relates to the type of switch 10 shown and described in Letters Patent No. 1,080,730, issued to me December 9, 1913. The mechanism described in that patent comprises among other parts, a contact carriage which is rocked by the movement of a 15 trip lever which is struck by the trolley carried by the car and which carries two arms which close a circuit when the carriage is rocked, the circuit remaining closed for a sufficiently long time to insure the throwing 20 of the track switch. In the patent referred to an electro-magnet in a shunt circuit is employed to return the carriage to its normal position, thus breaking the circuit.

My present invention consists in mechanical means for accomplishing this result, thus 25 allowing the electro-magnet which in my former patent was part of the main instrument to be located at a distance therefrom, for example, on a post by the roadside, proper wire 30 connections being made with the instrument.

It also consists in certain details which render the device as a whole more efficient.

My invention will be understood by reference to the drawings in which it is shown in 35 its preferred form.

Figure 1 is a side elevation of a circuit controller embodying my invention, the side walls being omitted. Fig. 2 is a similar view, enlarged, of the carriage-operating 40 mechanism, a portion being broken away to show its interior construction. Fig. 3 is a plan of the carriage. Fig. 4 is a detail of a portion of the carriage-detainer and the end of the latch which engages therewith. Fig. 45 5 is a sectional detail of the dashpot which forms part of the carriage-detainer. Fig. 6 is a front view of the switch circuit closer. Figs. 7, 8 and 9 are respectively a plan, a side view and an under view of the rail by 50 which my device is attached to the trolley wire. Fig. 10 shows the bent portion of the trolley wire. Fig. 11 is a section on line x-x of Fig. 8. Fig. 12 is a plan of the

track switch operating box, and Fig. 13 a side elevation thereof broken away to show 55 the journal box locking means, as well as other parts as preferably arranged. Fig. 14 is a detail perspective view of the journal box and key block.

The means for supporting my device on 60 the trolley wire is in the main fully described in my patent above referred to. The rail is shown at A and the trolley wire at A¹. As shown, however, in Figs. 9 and 11 the rail is provided with reinforcing shoes a 65 bolted to the rail as at a¹ which receive the wear of the trolley. These shoes are interchangeable and can be easily replaced when worn without removing the rail and apparatus from the trolley wire. As in my 70 said patent, the instrument is preferably mounted on two wooden blocks B triangular in cross section which are attached to the upper side of the rail A to form a flat flooring on which rests a metal plate B¹. An 75 opening B² through this plate, the blocks and the rail allows the trip lever C to pass down into the path of the trolley. The trolley wire A¹ is bent as shown in Figs. 9 and 10 and held in place and out of the way of 80 the opening B² so as not to interfere with the movement of the trip lever C and in contact with the metal plate B¹ by screws a². The rail and its connecting parts are attached to the trolley wire by clench ears a³ having 85 threaded extensions a⁴ which pass up through the rail A and are held in place by nuts. The clench ears are insulated from the rail A, thus insulating the rail from the trolley wire.

The frame for the controller comprises a bent plate D of insulating material which is mounted on a wooden baseboard D¹ or otherwise insulated from the metal base-plate B¹ which is in the circuit of the trolley 95 wire and on which the baseboard D¹ or its equivalent rests. Partitions of insulating material E and F are erected between the baseboard D¹ and the under side of the bent plate D and in addition two plates G of insulating material are mounted on the baseboard, each carrying a block g on its outer side, the space between the plates G and blocks g serving as a chamber within which the detaining mechanism operates. Only one of 100 the plates G is shown. Each block carries a

metallic plate g^1 to serve as an electric contact as below described.

The trip lever C is preferably made of non-conducting material and is hung on a pin c which is mounted in bearings formed in two uprights H which extend from the baseboard D^1 to the plate D. These uprights are alike and are mounted opposite each other, one on each edge of the baseboard D^1 . One only is shown. The lever C has a hook or engaging portion c^1 which is preferably shod with metal to engage the hooked end of a link K^1 which hangs from the carriage. The carriage is also mounted in the uprights H and comprises a shaft K on which are mounted to move therewith three arms, two of which K^2 are located one at each end of the shaft K and the other K^3 midway between the ends of the shaft. Two cross-bars k , k^1 connect the rear ends of these three arms. Midway between the ends of the cross-bar k^1 the link K^1 is loosely hung. To hold it on the cross-bar so that it will register with the trip lever I prefer to make its upper end forked and to bind each fork around the cross-bar k^1 , one fork on each side of the arm K^3 . It will be noted that one end of the carriage is overweighted so that it normally lies in the position shown in Fig. 1.

Upon the shaft K are mounted two contact arms K^4 in such a manner that the shaft and arms K^2 and K^3 may have a movement independent of the arms K^4 . The arms K^2 have at their outer ends tabs k^2 which normally rest on the arms K^4 and they are so held by a torsion spring K^5 wound on the shaft K on both sides of the arm K^3 . The winding of the two ends of the spring is in opposite directions, the extremities of the spring being attached to the arms K^4 and the two parts of the spring being connected by the loop k^3 which rests on the arm K^3 , this arrangement being such that when the link K^1 is pulled down by the trip lever C the farther ends of all the arms K^2 , K^3 and K^4 will be lifted. The arms K^4 have terminals k^4 at their outer ends which as shown are pieces of metal tubing each capable of rotation on its arm so as not only to make a good electrical contact with the under side of the plates g^1 which are shaped to afford a proper surface for the purpose but also with the idea that they will turn from time to time on their axes and so distribute the wear. The same result—that is, a constantly-changing contact point—might be otherwise attained. In their upward movement the ends of the arms K^4 will strike the plates g^1 which are carried by the blocks g, before the trip lever C has released the link K^1 so that the free ends of the arms K^2 and K^3 will be given a still further movement (see dotted lines 85 in Fig. 2). By means of the spring K^5 a

firm contact between k^4 and g^1 is secured and it is maintained with increasing force during the additional upward movement of the arms K^2 and K^3 and means are preferably provided to slow down the return movement of these arms after the trip lever has released the link so that this contact will be maintained for a sufficient time to secure the electrical operation of the track switch. In my said patent, the delaying of the breaking of the electric contact between the carriage and the terminals is brought about by electric means. In the present case mechanical means are shown and while various forms of mechanism for delaying motion known in the art might be used, I prefer to use the following:—L is a dashpot the lower part of which may be filled with mercury, glycerin or other viscous fluid. L^1 is a floating piston which fits sufficiently loosely in the dashpot to allow the slow escape of the liquid around its edge so that it may move vertically therein. Its specific gravity must be such that it will lie normally at the surface of the liquid in the dashpot. The piston L^1 is connected by a piston rod l with an arm l^1 mounted on a shaft l^2 which turns in bearings in an extension L^2 of the dashpot L. Through one end of the shaft l^2 passes a pin l^3 the upper end of which is connected with a connecting rod L^3 the farther end of which is pivotally connected with the upper end of the lever L^4 . This lever is pivoted at l^4 between the plates G, and its lower end is brought outward and terminates in a hook l^5 (see Fig. 4) which lies in the path of the wedge-shaped end of the arm K^3 . The arm K^3 carries a leaf spring k^5 on one side on the end of which is a wedge-shaped shoe or latch k^6 which thus has a lateral movement so that as the arm rises the shoe rides around the point of the hook l^5 and when it has passed above the hook resumes its normal position overlapping it. The relation of these parts will be understood from Fig. 4 where the normal position of the shoe or latch and the hook is shown. It will be seen that the lifting of the latch will cause it to engage the side edge of the hook which will push it to one side until it gets above the hook when it will spring back and rest in the hook. When the trip lever C releases the link K^1 the spring K^5 will pull down the arm K^3 and its end k^5 will press upon the hook l^5 and turn the lever L^4 , throwing the rod L^3 to the left (see Fig. 2) and cause the piston L^1 to be moved downward through its controlling fluid. This downward movement will be slow, its speed depending upon the liquid used and the relative diameters of the piston and the dashpot. When the hook l^5 and the arm K^3 separate the spring which is still under tension will move the carriage 130

toward its inoperative position. Cushions h^1 are preferably provided to receive the impact of the ends of the arms K^4 when they drop.

5 The circuits in the device (except the shunt coil for returning the carriage which is omitted) are like those in my said patent.

M is the coil of the car-circuit electromagnet. One end of the coil M is electrically connected with the metal plate B¹ which is always in contact with the trolley wire by the wire b and the binding screw b¹, and the other end with the rail A by the wire b² and binding screw b³. The coil M is dormant therefore unless a car is drawing current from the trolley wire through its trolley which is running on the rail A, the circuit then being from the trolley wire to the plate B¹, binding screw b¹, wire b, coil M, wire b², binding screw b³ and rail A. When this coil M is energized its core M¹ attracts its armature m which is pivoted at e to the plate E. As in my said patent, the armature m is connected to the yoke switch M² by a connecting rod m¹ loosely connected to said armature, the yoke switch being normally in contact with the terminal m². When the armature m is attracted it throws the yoke switch out of contact with the terminal m² and into contact with the terminal m³. The loose connection between the armature m and the yoke switch M² is such that the armature may complete its stroke and insure a good contact between the yoke switch and its terminal.

The circuit of the circuit-locking magnet as shown is as follows: One of the plates g¹ is connected by the wire g² with the post n² (shown in the form of a screw eye). This post n² is connected with a spring plate n³ on the baseboard D¹ preferably by a fuse or wire of high resistance n made in two parts soldered together as at n¹ with a solder having a low melting point. The plate n³ is connected by the wire b⁴ with the wire b which, as stated above, is connected with the metal plate B¹. The plate n³ is preferably a spring plate so that the fuse wire may be easily attached to it. The other plate g¹ is electrically connected with one end of the coil N of the circuit-locking magnet, the other end of this coil being connected by wire n⁵ to the yoke switch M² by which current runs to either the terminal m² or the terminal m³ and by wires m⁴ or m⁵ to the appropriate part of the track switch. The yoke switch is preferably made of iron to be held in place by the attraction of the core N¹ when the coil N is energized. When the trip lever C has lifted the ends of the arms K⁴ into contact with the plates g¹ the current will pass from the trolley wire and the metal plate B¹ through the branch of the wire b, plate n³, wire n, post n², wire n⁴, plate g¹, carriage arms K⁴ and their connec-

tions to the other plate g¹, coil N, wire n⁵, yoke switch M² and then to either the terminal m² or m³ according to the position of the yoke switch. It will be noted that if the car is drawing current through the coil M the yoke switch will remain in contact with the terminal m². It will also be noted that when the carriage is in its contacting position there will always be current passing from the trolley wire through the coil N and yoke switch M² to one of the track switch magnets, which one depending upon which the yoke switch is contacting with, m² or m³. The yoke switch is preferably provided with spring contacts m⁶ of copper or the like.

The track switch may be of any usual construction. The mounting of its operating mechanism is shown in Figs. 12, 13 and 14 where P is the track and P¹ is the switch tongue which has a plate p projecting therefrom laterally. To this plate p is attached a connecting rod P² which is connected to an arm p¹ carried by the shaft p² which also carries a second arm p³ connected by a connecting rod p⁴ with the plunger p⁵ of solenoids P³, P⁴. One of the solenoids P³ is connected with the wire m⁴ and the other with the wire m⁵. Both solenoids are grounded. The shaft p² is controlled by a spring P⁶. The journal boxes in switches of this class are usually held in place by bolts or screws. I prefer, however, the construction shown where each journal box p⁶ is in the shape of a truncated wedge, the recess in the casting which supports it being shaped at one side to receive it. Each journal box is grooved as at p⁷, p⁸, one groove p⁷ being adapted to fit a rib on the casting and the other p⁸ to fit a rib p⁹ on the key block p¹⁰. This key block p¹⁰ is of complementary shape and slips down into said recesses driving the journal box p⁶ into place and is held in position by a spring p¹¹ the upper end of which bears against a plate which projects from the top of the casing, and is centered by the pin p¹². The casing is preferably mounted on a hollow concrete foundation P⁶ sufficient in size to contain the solenoid and to afford plenty of room for the dirt which usually collects in switches of this kind and for all necessary drainage.

The details of my device may be varied in many ways without departing from the spirit of my invention.

What I claim as my invention is:—

1. In a device of the kind described, a circuit closer normally out of circuit, trolley-operated means for moving it to close its circuit, and automatic mechanical means for detaining and releasing it whereby it may return to its normal position.

2. In a device of the kind described, a circuit closer normally out of circuit, trol-

- ley-operated means for moving it to close its circuit, and a yielding support for holding it temporarily in its circuit-closing position.
5. 3. In a device of the kind described, a circuit closer normally out of circuit, trolley-operated means for moving it to close its circuit, yielding means for holding it temporarily in its circuit-closing position
- 10 and thereafter allowing it to resume its normal position, said means comprising a lever adapted to be temporarily engaged by said trolley-operated means and be moved by it into disengaging position whereby the said 15 trolley-operated means will be released.
4. In a device of the kind described, a circuit closer normally out of circuit, trolley-operated means for moving it to close its circuit, mechanism for returning it to its 20 normal position, and mechanical means one member of which is carried by said circuit closer to detain said circuit closer in its return movement.
5. In a device of the kind described, a 25 circuit closer normally out of circuit and comprising two arms, terminals adapted to be engaged by said arms, a latch, and connections between said latch and said arms and comprising a spring whereby said latch
- 30 may have a movement independent of said arms, a yielding member adapted to engage said latch, and means whereby the movement of said yielding member will be controlled.
- 35 6. In a device of the kind described, a circuit closer normally out of circuit and comprising two arms, terminals adapted to be engaged by said arms, a latch, and connections between said latch and said arms 40 and comprising a spring whereby said latch may have a movement independent of said arms, a yielding member adapted to engage said latch, and means comprising a dashpot having a piston and connections between 45 said piston and said yielding member whereby the movements of said yielding member will be delayed.
7. In a device of the kind described, a circuit closer comprising a shaft, two contact 50 arms independently mounted thereon, two holding arms mounted thereon to turn therewith, yielding means adapted to hold said holding arms normally in contact with said contact arms, a latch member also controlled 55 by said yielding means and adapted to move with said holding arms independently of said contact arms, and means adapted to engage said latch member temporarily when said holding arms and said contact arms are 60 out of contact.
8. In a device of the kind described, a 65 rockable circuit closer, a latch member carried thereby and comprising an arm, a spring attached to one side thereof, a latch attached to the end of said spring whereby

- it may have a yielding movement laterally of said arm, and a detaining mechanism comprising a hook located in the line of movement of said arm and adapted to be engaged by said latch and move it laterally 70 during the upward rocking of said circuit closer and thereafter to receive and retain it during a portion of its downward movement.
9. In a device of the kind described, a 75 dashpot, a piston located therein, a connecting rod connected thereto, a swing hook also connected to said connecting rod, a rockable circuit closer and means for rocking it comprising a trip lever and a link carried by 80 said circuit closer and adapted to be engaged by said trip lever, and a latch mounted on said circuit closer and adapted when said circuit closer is rocked to engage said hook.
10. In a device of the kind described, a 85 circuit controller, comprising a normally open switch operating circuit, means positively actuated by the trolley wheel of a car to close said switch circuit, and yielding means of resistance whereby said normally open circuit is automatically opened within a predetermined time limit.
11. A normally open electric circuit 90 switch, means adapted to engage said switch and move it to close its circuit, said means being operable by the trolley wheel of a passing car, and means whereby said switch is thereafter allowed to open within a predetermined time limit, said means comprising 95 switch-holding means separable from said switch and a dashpot connected to said switch-holding means.
12. A normally open switch operating 100 circuit, a trolley actuated switching member adapted to close said normally open circuit, two contact arms comprised in said switching member, said contact arms carrying detachable roller contacts adapted to close the normally open switch operating circuit, substantially as described.
13. In a device of the kind described, a 105 switch to close a normally open circuit having two breaks therein adapted to be closed simultaneously, means operable by a passing car to close said switch, and automatic yielding means comprising a dashpot whereby said electric circuit switch will occupy a predetermined time in returning to its normal position.
14. In a device of the kind described, a 110 normally open electric circuit switch, means operable by the trolley wheel of a passing car to close said electric circuit switch, a plurality of contacts comprised in said electric circuit switch, and yielding means comprising a dashpot to retard the return of said switch to its normal position whereby said switch will occupy a predetermined time in returning to its normal position.

15. In a device of the kind described, a normally open electric circuit switch, means operable by the trolley wheel of a passing car to move said electric circuit switch positively into closing position, automatic mechanical means for returning said switch member to its normal position and a retard-

ing mechanism operable to delay the return of said switch member for a predetermined time.
